PORTABLE ELECTRIC HAMMER

Ralph H. Maxwell and Frederick J. Weidling,
Wilmette, Ill.

Application June 6, 1932. Serial No. 615,678

9 Claims. (Cl. 255—42)

Our invention relates to improvements in portable electric hammers, and it consists in the combinations, constructions, and arrangements herein described and claimed.

- 5 An object of our invention is to provide a portable electric hammer in which vibration is reduced to a minimum, and which may be operated for a long period of time without tiring the operator.
- 10 A further object is to provide a portable electric hammer which will not become heated through continuous and prolonged operation.
- 15 A further object is to provide a novel portable electric hammer which will perform a given amount of work in a minimum length of time.
- 20 A further object is to provide a portable electric hammer in which novel shock-absorbing means is provided.
- 25 A further object is to provide a portable electric hammer having novel means for rotating a tool associated therewith when the device is in operation.
- 30 A further object is to provide a portable electric hammer which in turn is provided with novel means for having a tool connected therewith.
- 35 A further object is to provide a portable electric hammer having novel means for lubricating certain parts thereof.
- 40 A further object is to provide a portable electric hammer which is simple and sturdy in construction, and which may be readily assembled and disassembled for being serviced.
- 45 Other objects and advantages will appear in the following specification, and the novel features of the invention will be particularly pointed out in the appended claims.

Our invention is illustrated in the accompanying drawings, forming part of this application, in which

Figure 1 is a longitudinal sectional view of the device.

Figure 2 is a view taken substantially along the line 2—2 of Figure 1, certain portions thereof being shown in elevation,

Figure 3 is a detail view of a portion of the device,

Figure 4 is a detail sectional view taken along the line 4—4 of Figure 1,

Figure 5 is a detail sectional view taken along the line 5—5 of Figure 1,

Figure 6 is a detail sectional view taken along the line 6—6 of Figure 1, and

Figure 7 is a detail sectional view taken along the line 7—7 of Figure 1.

In carrying out our invention, we provide a housing 1 having a chamber 2 therein and provided with threaded end portions 3 and 4. The housing 1 comprises in part an outwardly projecting portion 5 having a cylindrical opening 6 therein for receiving a bearing member 7. A gear 8 is rotatably mounted in the chamber 2 and is provided with a shaft portion 9 which is rotatably positioned in the bearing member 7. The gear 8 is further provided with an eccentrically positioned cam portion 10.

The shaft portion 9 and the cam portion 10 may be integral with the gear 8 or fixedly connected therewith in any suitable manner. An annular plate member 11 is positioned on the shaft portion 9 between the cam portion 10 and the housing for properly positioning the gear 8 and the cam portion 10.

A connecting pin 12 is fixedly connected with the gear 8 and is eccentrically positioned with respect thereto. A connecting rod 13 has one end 14 pivotally mounted on the connecting pin 12 and is retained thereon by any suitable means, such as a cotter pin 15. The connecting pin 12 may be provided with an annular flange 80 portion or a ring member 16 positioned between the connecting rod 13 and the gear 8 for properly positioning the connecting rod with respect to the gear. The end 17 of the connecting rod extends within a recess 18 of a piston member 19 and is pivotally connected with the piston member 19 by any suitable means, such as a connecting pin 20. The piston member 19 is slidably disposed in a cylindrical chamber 21 of a reciprocable hammer member 22.

The hammer member 22 is provided with an annular recess in the cylinder wall adjacent an end thereof for receiving a retaining ring 23. The retaining ring is for the purpose of preventing the piston 19 from being accidentally moved out of the cylinder chamber 21. The hammer member 22 is slidably disposed in a sleeve member 24 and is provided with reduced portions 25 which in turn provide spaces 26 between the hammer member and the sleeve 24, which aid in reducing the friction between the hammer member and the sleeve.

The hammer member 22 is provided with a solid reduced end portion 27. The sleeve 24 has an end portion thereof positioned within the housing 1 and terminating in a circular row of teeth 28. The sleeve 24 is provided with a circumferential flange portion 29 for engagement with the housing 1 for positioning the sleeve 24 with respect to the housing.

The housing 1 is provided with an internal flange portion 30. A resilient means is positioned between the hammer member 22 and the flange portion 30, and comprises a retaining band 31 which is angular in cross section and in engagement with the flange portion 30.

A cushioning band 32 is positioned in engagement with the band 31 and between the band 31 and an auxiliary band 33. The cushioning band 32 may be of any shock-absorbing material, such as rubber.

A tubular casing 34 is disposed over the sleeve 24 and is provided with an internally threaded end portion for being connected with the end portion 4 of the housing 1. The casing 34 is provided with an internal and circumferential flange portion 35 disposed in spaced-apart relationship with respect to the flange portion 29 of the sleeve 24.

A helical spring 36 is positioned between the flange portions 29 and 35 and is for the purpose of yieldingly retaining the sleeve 24 in a given position, at which time the flange 29 is in engagement with the housing 1.

It will be noted at this time that the piston 19, the hammer member 22, and the sleeve 24 are provided with openings 37, 38, and 39, respectively, the purpose of which will be herein-after set forth.

As shown in Figures 1 and 3, a reciprocating and oscillatory pawl member 40 is positioned between the gear 8 and the plate member 11 and is provided with an elongated opening 41 therein for receiving the cam portion 10. The pawl member 40 is also provided with an elongated opening 42 therein for receiving a pin 43 which may be threaded for being connected with the housing 1 and locked in engagement therewith by a nut 44. The pawl member 40 is provided with teeth 45 in engagement with the teeth 28 of the sleeve member 24 for rotating the sleeve member when the pawl member is oscillated. The pawl member 40 may also be provided with an arcuate-shaped end 46.

The housing 1 may be provided with a bracket portion 47 which may be connected with the housing by any suitable means, such as a set screw 48. The bracket member is provided with a projecting portion 49 which is positioned in spaced-apart relation with respect to the end 46 of the pawl 40 and is provided with an opening 50 therein for receiving a spring 51 which bears against a spring-pressed member 52 in engagement with the arcuate-shaped end portion 46 of the pawl 40 for yieldingly retaining the teeth 45 of the pawl member in engagement with the teeth 28 of the sleeve 24. Thus it will be seen that when the cam portion 10 is rotated that the pawl member 40 will be oscillated for rotating the sleeve 24.

The sleeve 24 is provided with an end portion 53 which extends therewithin and may be connected in any suitable manner, such as by sweating or welding. The end member 53 is provided with a cylindrical recess 54 therein which is substantially concentric with the sleeve 24. A plate member 55 is movably disposed within the recess 54 and may be retained therein by any suitable means, such as a split ring 56 in engagement with the end member 53.

The end member 53 is further provided with a passageway 57 therein which is substantially concentric therewith. A portion 58 of the passageway 57 may be hexagonal in cross section, while a portion 59 of the same passageway may

be circular in cross section for receiving the stem 60 of a tool having corresponding hexagonal and circular portions so that the tool may be rotated when the sleeve 24 is rotated.

A cap member 61 may be connected with the end member 53 by any suitable means, such as having a threaded portion 62 thereof connected with a threaded portion 63 of the end member 53. A split collar 64 is disposed within the cap member 61 and comprises a pair of collar portions 65 and 66. The split collar 64 has a portion 67 thereof disposed in spaced-apart relationship with respect to the stem 60 of the tool and another portion 68 thereof of reduced diameter and adapted for engagement with the tool.

A resilient band 69 of any suitable material, such as rubber, encircles the reduced portion 68 of the split collar 64 for holding the collar in engagement with the stem of the tool. The stem 60 of the tool may be provided with a pin 70 extending therethrough and projecting beyond diametrically-opposed sides thereof for engaging the reduced portion of the split collar 64 whereby the stem of the tool may be retained within the collar. The stem 60 may be provided with projecting portions or lugs in lieu of the pin 70, if so desired.

The cap member 61 is provided with a constricted end portion 71 for retaining the split collar 64 and the resilient band 69 therewithin. The housing 1 is provided with an opening 72 therein for receiving a cover member 73. The cover member 73 may be connected with the housing by any suitable means, such as screws, not shown.

A pad 74 of absorbent material is disposed within the cover member 73 and may be connected therewith in any suitable manner. The absorbent pad 74 is provided with an internally projecting portion 75 which is positioned for engaging the connecting pin 12 during each revolution of the gear 8. The absorbent pad 74 may be saturated with oil which will be transmitted through the projecting portion 75 of the pad to the connecting pin 12 for lubricating the bearing surfaces between the connecting pin and the connecting rod.

A motor housing 76 has one end connected with the threaded end portion 3 of the housing 1 and is provided with an end portion 77 which may be fixedly connected therewith in any suitable manner, such as by welding. A motor is disposed in the housing 76 and has the field magnet 78 thereof fixedly connected with the end portion 77 by any suitable means, such as bolts 79.

The armature 80 of the motor is provided with bearing portions 81 and 82, the bearing portion 81 being disposed in a recess 83 of the end portion 77, and the bearing portion 82 being disposed in a retaining member 84 which is positioned between the housing 1 and the motor housing 76 and fixedly held in position by means of an internal flange portion 85 integral with the motor housing 76. The retaining member is provided with an opening 86 through which the shaft 87 of the armature extends.

A gear 88 is mounted on the shaft 87 and is in mesh with the gear 8 so that the gear 8 may be rotated when the motor is in operation. The motor housing 76 and the end portion 77 are provided with openings 89 therein for receiving brushes 90, which, of course, comprise a part of the motor and are associated therewith.

in the conventional manner. The end portion 77 of the housing 76 is provided with a projecting portion 91 which in turn is provided with a reduced portion 92 for forming a shoulder portion 93. 5

A cover member 94 is provided with a central opening 95 therein through which the reduced portion 92 extends and engages the shoulder portion 93 for being properly positioned with respect to the projecting portion 91. A ring 96 extends over the end of the projecting portion 91 and has a pin 97 extending therethrough and also through the projecting portion 91 for connecting the cover member 94 with the projecting portion 91. 10

The cover member 94 is provided with a hollow handle portion 98 which contains a switch mechanism 99. A switch actuating member 100 is operatively associated with the switch mechanism and extends through an opening in the handle portion so that the same may be manually actuated by an operator. An insulating plate 101 is fixedly connected with the cover member 94 by any suitable means, such as screws 102, and in like manner, an insulating plate 103 is connected with the end portion 77 of the motor housing 76. 15

Contact elements 104 and 105 are connected with the insulating plate 101 and are in engagement with contact rings 106 and 107, respectively, 20 which are mounted in the insulating plate 103, and which are disposed in concentric and spaced-apart relationship. 30

The end portion 77 is provided with openings 108 through which conductors 109 may extend for providing electrical communication between the contact rings and the magnetic field of the motor. The contact elements 104 and 105, together with the switch mechanism 99, are in communication with a source of current by 35 means of conductors 110. 40

The motor housing 76 and the cover member 94 are provided with openings 111 and 112 therein so that air may circulate through the motor housing 76 for cooling the motor. A fan 113 is 45 mounted on the armature shaft 87 for circulating the air through the motor housing. 50

On referring to Figures 1 and 7, it will be noted that the housing 1 is provided with a recess 114 through which the pawl member 40 extends. The bands 31 and 33 are provided with lug portions 115 extending within the recess 114 and positioned on opposite sides of the pawl member for retaining the bands in position. The lug portions 115 are disposed in spaced-apart positions with respect to the pawl member so as not to hinder the movement thereof. 55

From the foregoing description of the various parts of the device, the operation thereof may be readily understood. When it is desired to 60 put the device in operation, the operator actuates the switch actuating member 100 for closing the circuit, thereby causing the motor to operate for reciprocating the piston 19 through the gears 88, 8, and the connecting arm 13. 65

In following through the operation of the device, it will be seen that as the piston 19 moves downwardly, it will compress the air in the chamber 116 between the piston and the hammer member, which will result in driving 70 the hammer member downwardly for striking the plate member 55. This impingement of the hammer member on the plate member 55 is transmitted to the stem 60 of the tool, thereby causing the tool to move into the material with 75 which it is in contact. 80

It will be noted, however, that when the plate 55 engages the shoulder portion 117 of the end portion 53 that the shock thereof is absorbed by the spring 36 which tends to yieldingly resist the movement of the sleeve 24 downwardly. When the piston 19 and the hammer member 22 have reached their extreme downward positions, the air in the chamber will be compressed momentarily but may escape through the minute openings 37, 38, and 39. 85

As the piston is moved upwardly, it will create a suction within the chamber 116, thereby causing the hammer member 22 to also move upwardly. As the hammer member approaches its extreme uppermost position, its speed will be lessened by reason of the air rushing through the openings 38 and 39 for overcoming the suction in the chamber 116. When the hammer reaches its uppermost position, however, it will engage the band 33 so that the shock thereof will be absorbed by the cushioning band 32. 90

It will be noted that at each rotation of the gear 8 and reciprocation of the piston 19 that the pawl member 40 is moved through an oscillation for rotating the sleeve 24 a portion of 100 a revolution which results in the stem 60 of the tool also being rotated a portion of a revolution. Thus it will be seen that when the device is in operation, not only will the hammer member be reciprocated at a great rate of speed, but also 105 that the tool will be rotated a portion of a revolution at each reciprocation of the hammer member. 95

If it is desired to dispense with the rotating feature of the device, it is merely necessary to 110 remove the pawl member 40. The pawl member and the cam portion 10 are of course so related that the sleeve member 24 will be moved through a portion of a revolution when the hammer member is moved through its up stroke. 115

It will be noted that the tool is so associated with the device that it cannot be driven out of engagement therewith when the device is operated without the tool being in engagement with material to be worked. This construction eliminates the danger of the tool being driven from the device when the switch member is accidentally operated for energizing the motor. The construction is such, however, that the tool may be readily removed or replaced by another. 120

The outwardly projecting portion 5 of the housing 1 may be provided with a pair of spaced-apart flange portions 118. A handle member 119 is provided with an elliptical-shaped portion 120 positioned between the flange portions 118 and 130 pivotally connected therewith by means of a pin 121 extending through the elliptical portion 120 and the flange portions 118. The handle 119 may be moved to the dotted line position 122, at which time the elliptical portion 120 will 135 engage the portion 5 of the housing for retaining the handle in its transverse dotted line position. 125

The advantages of this feature are that the device may be more easily controlled when in operation, and additional pressure may be exerted on the device for holding the tool in engagement with the work. 140

The projecting portion 5 may be provided with an opening therein for receiving a plug or screw member 123 so that the bearing 7 containing 145 the shaft 9 may be lubricated.

We claim:

1. A portable power hammer comprising a housing, a motor mounted in the housing, a reciprocable sleeve operatively connected with the 150

with a driven gear rotatably mounted in the housing, a sleeve operatively associated with the housing and movable with respect thereto, a reciprocable hammer slidably disposed in the sleeve, a piston slidably disposed in the hammer and operatively associated therewith, a connecting rod operatively connected with the driven gear and the piston for reciprocating the hammer when the motor is operated, a casing portion connected with the gear housing and positioned exteriorly with respect to the sleeve, said sleeve and casing portion being provided with spaced- apart flange portions, resilient means positioned between the flange portions for yieldingly retaining the sleeve in a given position, said sleeve being provided with a toothed end portion, a cam portion associated with the driven gear, and a pawl member associated with the cam portion and in engagement with the toothed portion of the sleeve, said pawl member being operable by the cam portion for rotating the sleeve when the driven gear is rotated.

RALPH H. MAXWELL.

FREDERICK J. WEIDLING.
